UNITED STATES PATENT OFFICE.

ARTHUR LOPEZ JIMINEZ, OF NEW YORK, N. Y., ASSIGNOR OF FORTY-FIVE ONE-HUNDREDTHS TO WILLIAM FREEMAN, FIVE ONE-HUNDREDTHS TO JOSEPH LOPEZ JIMINEZ, AND ONE-TWENTIETH TO JUAN M. RIGAU CARRERA, OF NEW YORK, N. Y.

WHEEL.

No. 901,907.

Specification of Letters Patent.

Patented Oct. 20, 1908.

Application filed July 1, 1907. Serial No. 381,689.

To all whom it may concern:

Be it known that I, ARTHUR LOPEZ JIMINEZ, of New York, in the county of New York and State of New York, have invented 5 certain new and useful Improvements in Wheels; and I do hereby declare the following to be a full, clear, and exact description of the invention, such as will enable others skilled in the art to which it appertains to 10 make and use the same.

My invention relates to an improvement in wheels and more particularly to such as are adaptable for use on motor vehicles,—the object of the invention being to provide 15 a construction which shall comprise a small number of parts, which can be manufactured cheaply without a sacrifice of strength and elasticity, but which on the other hand will possess great strength and which will not 20 be liable to buckle and which will afford adequate elasticity and avoid liability to careening when the vehicle is subjected to abnormal lateral strain.

With this object in view the invention 25 consists in certain novel features of construction and combinations of parts as hereinafter set forth and pointed out in the claims.

In the accompanying drawings, Figure 1 30 is a face view of a wheel embodying my improvements. Fig. 2 is a sectional view of the same, and Fig. 3 is a sectional view illustrating the formation of the various parts of the wheel members. Fig. 4 is a 35 sectional view of the members constituting the body portion of the wheel, and Fig. 5 is a similar view of the members composing the tire portion.

1 represents a hub and 2, 2, illustrate the 40 two members of the body-portion of the wheel which are disposed between the members or plates 3 of the hub. The respective body-members are made of sheet metal and their central portions are flat and disposed 45 parallel with each other. Between the central flat-portions 4 of the body-members a wooden spacer 5 is placed and the parts are secured to the hub-plate by means of bolts 6 which pass through said hub-plates, the 50 central flat-body portions of the wheel-members and the spacer 5. Each section of the wheel body-portion is made with an annular bead 7 (semi-circular in cross-section) and the web between this annular bead and the

central flat-portion 4 of the body-section is 55 made with an annular series of radial beads 8, each of which is semi-circular in cross-section. Thus it will be seen that when the two members or sections of the wheel body-portion are placed together the beads 7 and 60 8 will project outwardly from respective sides of said body-portion. Each plate or section of the body-portion beyond the annular bead 7 is made with radial beaded portions 9 in planes parallel with the radial 65 bead 8. At the periphery of each plate or section of the body-portion of the wheel an annular bead 10 is formed and when the parts are assembled, as hereinafter explained, the tire portion of the wheel will inclose the 70 outer annular bead 10, as shown in Fig. 2.

The tire-portion of the wheel comprises two sheet metal rings 11, 11, bulged outwardly to form a chamber for the reception of a pneumatic tube 12, against the inner 75 side of which the outer annular beads 10 of the body-portion of the wheel have a bearing. Beyond their bulged portions, the plates or rings 11 are made with parallel parts 13 between which spacing blocks or 80 spools 14 are placed and through these parallel portions of the rings or plates 11 and through the blocks or spools 14, bolts 15 are passed for securing the two rings or plates 11 together. Beyond the parallel portions 85 13 of the rings or plates 11 the latter are provided with lips or flanges 16 which embrace a cushion tire 17 and hold the same in place. Inwardly of the bulged portions of the plates 11, the latter are brought together 90 at intervals and secured by means of bolts 18. Those portions of the inner edges or flanges of the rings or plates 11, which form the tire portion of the wheel, constitute 95 guide-ways through which the radial beaded portions 9 of the wheel-body pass and in which they can have lateral play,—said guide-ways being made elongated as shown in Fig. 2.

From the construction and arrangement of 100 parts above described it will be seen that the beaded periphery of the body portion (being cylindrical in cross-section) will have an extended bearing against the inner face of the pneumatic tube and press the same outwardly, as shown in Fig. 2. The body-portion of the wheel will therefore, not only 105 have a bearing against the pneumatic tube

which will cause a radial pressure but that said body-portion of the wheel will also have a somewhat lateral bearing against the pneumatic tube which will result in preventing overturning of the wheel when the vehicle to which it is attached is subjected to abnormal lateral strain.

It is of course apparent that the body-portion and the tire portion of the wheel must have vertical movement relatively to each other and this is permitted by the elongated guide-ways 19 of the tire-portion, through which the radial beaded portions 9 of the body-portion of the wheel pass.

Various slight changes might be made in the details of construction of my invention without departing from the spirit thereof or limiting its scope and hence I do not wish to restrict myself to the precise details herein set forth.

Having fully described my invention what I claim as new and desire to secure by Letters-Patent, is,—

1. A wheel comprising a sheet-metal body-portion and a tire-portion, said body portion comprising two plates secured together and each provided with a peripheral bead, the peripheral beads of the respective sheet metal body members coöperating to form a hollow rim disposed within the tire-portion and a pneumatic tube within the tire portion and constituting a bearing for the hollow rim formed by the peripheral beads on the plates of the body-portion.

2. A wheel comprising a body-portion, a tire-portion and a pneumatic tire within the tire-portion, said body portion comprising two members secured together and having

40 peripheral beads disposed within the tire-portion and bearing against the pneumatic cushion therein, each plate of the body portion having beads between its center and the tire-portion and said plates of the body-portion having radial beaded portions passing into the tire-portion and terminating at the 45 peripheral beads of the plates of the body-portion, and said tire-portion having guide-ways in which the radial beaded portions of the wheel body can have radial and lateral movement.

50 3. A wheel comprising a body portion, a tire portion movable relatively thereto and a pneumatic cushion within the tire-portion and bearing against the body portion, said body portion comprising two plates having 55 flat parallel central portions secured together, each of said plates having an outwardly projecting annular bead removed a distance from the flat central portion and also having radial beads extending from the 60 flat-central portion to the annular bead, and said plates also having radial beaded portions which enter the tire-portion and the peripheries of the plates composing the body portion of the wheel having beads located 65 within the tire-portion of the wheel and bearing against the pneumatic cushion within the latter.

In testimony whereof, I have signed this specification in the presence of two sub- 70 scribing witnesses.

ARTHUR LOPEZ JIMINEZ.
